UNITED STATES PATENT OFFICE.

PLATO G. EMERY, OF CHICAGO, ILLINOIS.

VESTIBULE-CURTAIN HANDLE.

Application filed November 26, 1926. Serial No. 150,852.

The present invention relates to handles by means of which the free ends of curtains employed in the vestibules of railway passenger cars are held stretched along the 5 sides of the passageway between two adjacent cars. In order to prevent injury to or destruction of such curtains in the event that two cars are uncoupled and drawn apart before the curtains are released, it is 10 the practice so to construct these handles that they will automatically release under a pull greater than normal but insufficient to injure the curtain or its supporting roller.

The object of the present invention is to 15 produce such an automatically releasing curtain handle which shall consist of a few simple rugged parts, and which shall be efficient in operation both under working conditions and conditions that require a curtain 20 to be released.

The various features of novelty whereby 25 my invention is characterized will herein-after be pointed out with particularity in the claims; but, for a full understanding 25 of my invention and of its objects and advantages, reference may be had to the following detailed description taken in connection with the accompanying drawing, wherein:

30 Figure 1 is an elevation of a fragment of a vestibule curtain, shown unrolled and fastened to a door jamb by a handle arranged in accordance with the present invention; and Fig. 2 is a section taken approximately 35 on line 2—2 of Fig. 1, showing only the tubular arm of the bracket and the spring within the same.

Referring to the drawing, 1 represents a curtain of any usual or suitable construction 40 having at its free end a stiffening rod 2. 3 represents the door jamb at the outer end of the vestibule of a car facing the one on which the curtain is mounted. On the door jamb is a hook 4 of any usual or suitable construction with which a handle on the free end of the curtain is to be engaged.

My improved handle consists of two principal parts, a bracket 5 and a bar-like handle forming member. The bracket may 50 take any usual or suitable form capable of being fastened to the curtain. Projecting from the bracket, in the plane of the curtain when unrolled, are two arms 7 and 8, the arm 7 being tubular and the arm 8 also 55 being conveniently made tubular. A notch 9 is cut into the upper side of the arm 7 at

the front end, and the handle forming member 6 projects down into this arm through the notch, being pivoted to the arm by a pivot pin 10 that lies nearer the inner than 60 the outer side of the arm. In other words, the pivot pin is between the longitudinal central axis of the arm 7 and the arm 8. The member 6 is extended beyond the pivot pin to form a heel 11. The inner side of 65 the arm 8 has a notch 12 cut into the end thereof. The parts are so proportioned and arranged that the handle forming member 6 may swing in the plane of the arms between a position in which the free end enters 70 the notch in the arm 8 and a position in which the member 6 is parallel to or makes an acute angle with the longitudinal axis of its supporting arm.

Within the arm 7 is a compression spring 75 13 between the front end of which and the heel of the handle forming member is a follower 14. Any suitable abutment may be provided for the rear end of the spring. In the arrangement shown, there are pins 15 80 extending transversely through the arm behind the spring, thus permitting the arm to be open at both ends without allowing the spring to drop out before the bracket 85 is attached to the curtain.

The spring is made strong enough to hold the handle forming member 6 in its working position, shown in full lines in the drawing. When an abnormal pull is exerted on the member 6, such as occurs when two cars 90 are drawn apart without first releasing this member from the hook with which it is engaged, the spring yields and permits the handle forming member to swing into the position shown in dotted lines in Fig. 1, 95 whereby it is freed from the engaging hook.

For the sake of convenience of manufacture, the arm 8 is employed as an abutment against which the free end of the handle forming member is normally pressed by the spring. However, the arm 8 may function simply as a guard to prevent the hook from freeing itself from the handle forming member by slipping lengthwise from the same. In either case, the arm 8 is preferably utilized as a guide for the free end of the handle forming member, holding the latter centered and preventing it from swinging in a direction except in a plane at right angles to its pivot.

It is desirable that, in the event of the breaking of the spring, which would other-

wise make it impossible to hold the curtain stretched, temporary repair of the handle be possible, even though the releasing function of the handle be destroyed. To this end, 5 I have provided the free end of the handle forming member 6 with a nose or tip 16 and provided the arm 8 with a transverse hole 17 that lies just in front of or outwardly from the nose or tip when the parts are in their 10 normal working positions. In the event of the breaking of the spring, a pin or nail may be inserted through the hole 17, thus transforming the handle into a rigid, non-releasing device which, however, serves effectively 15 to hold the curtain properly stretched.

While I have illustrated and described with particularity only a single preferred form of my invention, I do not desire to be limited to the exact structural details thus 20 illustrated and described; but intend to cover all forms and arrangements which come within the definitions of my invention constituting the appended claims.

I claim:

25 1. A curtain handle comprising a handle-forming member pivoted at one end, a stationary abutment with which the other end of said member engages, and a spring acting on said member in the vicinity of the pivoted end normally to hold said member against said abutment and permit it to swing away therefrom when a predetermined pull is exerted on said member.

30 2. A curtain handle comprising a handle-forming member pivoted at one end, a stationary guard in the path of the swinging movement of the free end of said member, and a spring acting on the pivoted end of said member tending to hold the opposite end 35 of the latter in operative relation to the guard and permitting it to swing clear of the guard under a predetermined pull on said member.

35 3. A curtain handle comprising a handle-forming member pivoted near one end, a spring acting on said member to hold said member in its working position during a normal pull on the same and permit it to swing into a release position under an abnormally great pull, and a stationary guard 40 cooperating with the opposite end of said member to prevent the handle-engaging member from slipping off endwise of said member when the latter is in its working 45 position.

4. A curtain handle comprising a handle-forming member pivoted at one end, a stationary abutment behind the other end, and a spring acting on said member normally to hold it against said abutment and permit it 60 to swing away therefrom when a predetermined pull is exerted upon the same.

5. A curtain handle comprising a bracket having two spaced arms projecting therefrom, one of said arms being hollow, a 65 handle-forming member spanning the space between the outer ends of said arms and pivoted to the hollow arm so as to be capable of swinging in the plane of said arms, and a spring in said hollow arm tending to hold 70 the free end of the said member in the vicinity of the outer end of the other arm.

6. A curtain handle comprising a bracket having spaced arms projecting therefrom, a handle-forming member spanning the space 75 between said arms and pivoted to one of the arms to permit swinging movement in the plane of said arms, a spring acting on the pivoted end of the said member yieldingly to hold the free end thereof in overlapping relation with the outer end of the second arm, said second arm having therein a hole in 80 position to receive a pin adapted to lie in the path of said member and prevent the free end from swinging outwardly.

7. A curtain handle comprising a bracket having spaced tubular arms projecting therefrom, a handle-forming member spanning the space between the outer ends of said arms, said member being pivoted to the outer 90 end of one of said arms, the second arm having a notch in the outer end to receive the free end of said member, and a spring in the first arm acting on said member, yieldingly holding said member in a position in 95 which its free end lies in said notch.

8. A curtain handle comprising a bracket having two spaced arms projecting therefrom, one of said arms being tubular, a handle-forming member spanning the space 100 between the outer ends of the arms and hinged to the tubular arm nearer the inner than the outer side, and a spring in said tubular arm pressing against said member and yieldingly holding it with its free end 105 engaged with the other arm.

In testimony whereof, I sign this specification.

PLATO G. EMERY.
